UNITED STATES PATENT OFFICE.

WALTER C. HILL, OF LONDON, ENGLAND.

WATER-TIGHT ELECTRIC BELL.

No. 865,038.

Specification of Letters Patent.

Patented Sept. 3, 1907.

Application filed May 19, 1906. Serial No. 317,717.

To all whom it may concern:

Be it known that I, WALTER C. HILL, a subject of the Kingdom of Great Britain, residing in London, England, have invented certain new and useful Improvements in Water-Tight Electric Bells, of which the following is a specification.

My invention relates to electrically actuated bells or alarms wherein the electric striking mechanism is enclosed within a water-tight metallic casing which forms the sounder or bell; and my improvements consist in certain particulars of construction which are hereinafter pointed out and described.

In the drawings Figure 1 is a side elevation of one of my improved bells, with a portion of the case broken away to show the interior mechanism, and Fig. 2 is a vertical cross-sectional view of the same taken on the line *xx* of Fig. 1, the casing however not being broken away as in that figure.

Similar letters of reference designate similar parts in both the figures.

A is the bell, which is formed of brass, bell metal, or other suitable material, either cast as a whole or stamped or spun in halves and afterward united, as shown in the drawings, the two corresponding halves being soldered together and to the inner band *a*. The head-piece B is formed of a suitable insulating material, such as vulcanite, red fiber, wood or composition, and it is firmly secured to the bell A by screws C passing through the head-piece and threaded into the bell, thus making a close, water-tight joint between the head-piece and the bell. A rod D, is inserted in the head-piece, its upper end being secured to a suitable bracket E, connection being made between its lower end and one end, *f*, of the electro magnetic coil F, by means of a contact screw *e*. A collar G, is secured around the neck of the head-piece B by means of screws *g g* passing through the collar and head-piece and threaded into and carrying an electro magnet H. The electric circuit is continued from the end *f* of the electro magnetic coil through a screw *i*, and a make-and-break contact spring I, supported by insulation *k*

upon the neck of the screw K which passes freely through the armature J' and into the magnet H, and by a connection from the armature spring J, through a suitable conductor *j*, to the electro magnet H, and completed through the screws *g g*, and the collar G, to which is attached the flexible lead *g'*, the other lead *e'* being attached to the bracket E.

By means of my improvements I obtain an air-tight and water-tight bell or alarm, the operative mechanism whereof is entirely contained within the sealed case of bell; and wherein the flexible leads are not carried into the bell itself, which is objectionable because of the danger of breaking the internal connections by rough handling or abnormal, accidental strains on the terminal wires, but in which the electric circuit is carried through the rigid screws which are employed to connect the electrical mechanism with the non-conducting head-piece and to sustain the device in a suitable position.

The case or bell A, being carried by the non-conducting head-piece B, is outside of the electrical circuit; and I thereby avoid the danger of short-circuiting the current, which is likely to happen where the casing itself forms part of the electrical circuit.

Having thus described my invention, what I claim and desire to secure by Letters Patent of the United States is:—

The combination, in an electrical alarm, of a non-conducting head-piece provided with electrical conductors passing therethrough, electrical striking mechanism supported by said head piece, and a hollow cylinder with flat, closed ends forming a resonant bell casing and having an opening through its circumference to permit the insertion of said striking mechanism therethrough, said opening being closed by said head piece whereby said bell-casing is carried free from other contact and outside of the electric circuit and forms a hermetically closed chamber completely inclosing said striking mechanism and adapted to be rung thereby.

WALTER C. HILL.
